UNITED STATES PATENT OFFICE.

MICHAEL J. POPOVICH, OF EAST PITTSBURGH, PENNSYLVANIA.

MORTISE-LOCK.

1,335,027.

Specification of Letters Patent. Patented Mar. 30, 1920.

Application filed May 7, 1918. Serial No. 233,025.

To all whom it may concern:

Be it known that I, MICHAEL J. POPOVICH, subject of the King of Serbia, residing at East Pittsburgh, in the county of Allegheny and State of Pennsylvania, have invented 5 certain new and useful Improvements in Mortise-Locks, of which the following is a specification.

This invention relates to a mortise lock 10 and has for its object to provide a lock of such class in a manner as hereinafter set forth, with a lock-bolt having a vertical and longitudinal movement when shifted to and from locking position, and said locking bolt 15 having means associated with the locking pin arranged within the keeper forming a part of the lock to prevent the locking bolt from being surreptitiously shifted to open the lock.

20 Further objects of the invention are to provide a mortise lock which is simple in its construction and arrangement, strong, durable, thoroughly efficient in its use, conveniently operated and comparatively inexpensive to set up.

With the foregoing and other objects in view this invention consists of the novel construction, combination and arrangement of parts as hereinafter more specifically described and illustrated in the accompanying drawings, wherein is found an embodiment of the invention, but it is to be understood that changes, variations and modifications can be resorted to which come within the 35 scope of the claims hereunto appended.

In the drawings wherein like reference characters denote corresponding parts throughout the several views:

Figure 1 is an elevation showing the elements of the lock in full lines in closed position and in dotted lines in open position.

Fig. 2 is an elevation of the actuating mechanism for the locking bolt.

Fig. 3 is a sectional detail illustrating the locking pin associated with a locking bolt.

Referring to the drawings in detail 1 denotes a locking bolt, which is substantially oblong in contour, and has its forward end 50 reduced to provide a nose 2, and a recess 3.

Suitably arranged within the lock casing 1^a, above the locking bolt 1, are roller bearings 4, against which the locking bolt 1, rides as it is shifted to and from locking position. Roller bearings 4, also arrest upward movement of the locking bolt 1.

Associated with the locking bolt 1, is an actuating mechanism therefor the purpose of which is to elevate said bolt 1, and further to shift the same longitudinally 60 to locking position. The said actuating mechanism consists of a toothed sector 5, pivotally mounted as at 6, and provided with an arm 7. The arm has a slotted extension 8, into which extends a pin 9.

The said actuating mechanism further includes a link 10, which is pivotally connected as at 11, to the arm 7, and also pivotally connected as at 12, to a lever 13, the latter is pivotally connected as at 14, to the 70 curved intermediate portion 15, of a shifting arm 16. The ends of the arm 16, are connected as at 17, to the locking bolt 1.

The extension 8 is arranged over the lever 13, and is slotted, and as before stated the 75 pin 9 extends into the slot thereof. The pin 9 is carried by the lever 13.

The said actuating mechanism further includes a supporting bar 18, having pivotally connected to each end as at 19, a link 20, and 80 the said links 20, are pivotally connected through the medium of the pivot 17, with the locking bolt 1. The supporting bar 18, is secured in the lock casing 1^a, provided for the locking bolt 1 and associated elements, in any suitable manner.

The reference character 21, denotes a keeper casing and which is formed with a slot 22, to permit of the passage of the forward end of the locking bolt into and out 90 of the said casing 21. Arranged within the casing 21, are rods 23, which carry a shiftable locking pin 24, the latter is controlled by a pair of springs 25, which are mounted on the rods 23, and interposed between the 95 rear wall of the casing 21, and the locking pin 24.

When the locking bolt 1, is in engagement with the pin 24, the springs 25, maintain the pin 24, against the wall 26 of the 100 recess 3.

For the purpose of restoring the locking bolt 1, to inoperative position when the latter is shifted clear of the locking pin 24 a spring 27 is employed which has one end 105 secured to the lock casing and the other end to the rear end of the locking bolt 1. The said spring 27, not only acts as a means to restore the locking bolt to normal or inoperative position when said bolt 110 is shifted clear of the locking pin 24, but when the locking bolt is in engagement

with the pin 24 said spring acts as a means to maintain the nose 2, against the pin 24.

Owing to the providing of the locking bolt 1, with a recess 3, and nose 2, and associating therewith the locking pin 24, it is obvious that it prevents the prying apart of the door and jamb.

The reference character 28 denotes a key, the ward 29 thereof being shown in engagement with one of the teeth 30, of the toothed sector 5.

When the key 28 is turned in the direction to move the locking bolt to locking engagement the sector 5 is shifted on its pivot in the direction indicated by the arrow, Fig. 1. This first causes an elevation of the locking bolt 1, after which the locking bolt is moved forwardly in a longitudinal direction until the nose clears the pin 24, when the bolt 1, will move downwardly and the pin 24 engage in the recess 3.

If the sector 5, is shifted in the direction of the arrow shown in Fig. 2, the arm 7, will engage the lever 13, elevate the bolt 1 and after the nose 2, clears the pin 24, the spring 27, will restore the locking bolt to normal or inoperative position.

What I claim is:

1. In a lock the combination with a spring controlled locking pin, of a locking bolt provided with a recess adapted to receive said pin to lock said bolt, a shifting arm pivotally connected to said bolt, and means connected with said shifting arm for elevating the arm and bolt and for further causing said shifting arm to move the bolt in a longitudinal direction to engage said pin.

2. In a lock the combination with a spring controlled locking pin, of a locking bolt provided with a recess adapted to receive said pin to lock said bolt, a shifting arm pivotally connected to said bolt, and means connected with said shifting arm for elevating the arm and bolt and for further causing said shifting arm to move the bolt in a longitudinal direction to engage said pin and means for arresting longitudinal shifting movement of the bolt in either direction.

3. In a lock the combination with a spring controlled locking pin, of a locking bolt provided with a recess adapted to receive said pin to lock said bolt, a shifting arm pivotally connected to said bolt, and means connected with said shifting arm for elevating the arm and bolt and for further causing said shifting arm to move the bolt in a longitudinal direction to engage said pin, and roller bearings for limiting the upward movement of the bolt and against which said bolt rides when shifted longitudinally to locking position.

4. In a lock the combination with a spring

controlled locking pin, of a locking bolt provided with a recess adapted to receive said pin to lock said bolt, a shifting arm pivotally connected to said bolt, and means connected with said shifting arm for elevating the arm and bolt and for further causing said shifting arm to move the bolt in a longitudinal direction to engage said pin, and a spring having one end connected to said bolt and its other end anchored.

5. In a lock the combination with a spring controlled locking pin, of a locking bolt provided with a recess adapted to receive said pin to lock said bolt, a shifting arm pivotally connected to said bolt, and means connected with said shifting arm for elevating the arm and bolt and for further causing said shifting arm to move the bolt in a longitudinal direction to engage said pin, and means for arresting longitudinal shifting movement of the bolt in either direction, and a spring having one end connected to said bolt and its other end anchored.

6. In a lock the combination with a spring controlled locking pin, of a locking bolt provided with a recess adapted to receive said pin to lock said bolt, a shifting arm pivotally connected to said bolt, and means connected with said shifting arm for elevating the arm and bolt and for further causing said shifting arm to move the bolt in a longitudinal direction to engage said pin, and roller bearings for limiting the upward movement of the bolt and against which said bolt rides when shifted longitudinally to locking position and a spring having one end connected to said bolt and its other end anchored.

7. In a lock the combination with a spring controlled locking pin, of a locking bolt provided with a recess adapted to receive said pin to lock said bolt, a shifting arm pivotally connected to said bolt, and means connected with said shifting arm for elevating the arm and bolt and for further causing said shifting arm to move the bolt in a longitudinal direction to engage said pin, and means for arresting longitudinal shifting movement of the bolt in either direction, and roller bearings for limiting the upward movement of the bolt and against which said bolt rides when shifted longitudinally to locking position, and a spring having one end connected to said bolt and its other end anchored.

In testimony whereof I affix my signature in the presence of two witnesses.
